SANITARY BANDAGE

Filed Oct. 20, 1928

INVENTOR.
Joseph Reich
BY Solon P. Schley ATTORNEY

UNITED STATES PATENT OFFICE

JOSEPH REICH, OF BROOKLYN, NEW YORK

SANITARY BANDAGE

Application filed October 20, 1928. Serial No. 313,655.

This invention relates generally to bandages and has more particular reference to a novel catamenial bandage.

The invention has for an object the provision of an article of the class mentioned which is of simple durable construction, desirable in use and efficient in action, and which can be manufactured and sold at a reasonable cost.

10 The invention proposes the use of an absorbent pad in the form of a block and made of cellulose, sponge, or cotton and suitably supported in a pad support having front and rear support loops arranged for connection with supporting straps in turn connected with a waist strap. The pad support is formed with a recess for accommodating the absorbent block pad which may readily slip into this recess and be removed therefrom.

15 For further comprehension of the invention, and of the objects and advantages thereof, reference will be had to the following description and accompanying drawings, and to the appended claims in which the various novel features of the invention are more particularly set forth.

In the accompanying drawing, forming a material part of this disclosure:

20 Fig. 1 is a perspective view of a device constructed according to this invention.

Fig. 2 is a perspective view of the waist strap used in the device.

25 Fig. 3 is a plan view of the pad support used in the device.

Fig. 4 is a perspective view of the absorbent pad of the device.

Fig. 5 is a vertical sectional view, taken on the line 5—5 of Fig. 3.

30 Fig. 6 is a view similar to Fig. 3, but disclosing a modification thereof.

Fig. 7 is a vertical sectional view, taken on the line 7—7 of Fig. 6 and showing the absorbent pad applied, and,

35 Fig. 8 is a perspective view of the pad shown in Fig. 7.

The reference numeral 10 indicates generally a waist strap consisting of a front section 11 and a rear section 12. The front section is permanently secured on one of its

ends to one of the ends of the rear section as at 13, and detachably secured at its other end as at 14. A front strap 15 is secured at one of its ends onto the front section 11 and is bent into a loop and secured at its free end upon a button 16 attached on the front section 11. Several button holes 16' may be formed in the strap 15, individually engageable on the button 16 for adjusting the size of the loop.

40 A pad support 17 consisting of a base 18 and sides 19 forming recess 20, is provided with a frame support loop 21 and a rear support loop 22. The front support loop 21 is engaged in the loop formed by the front strap 15 and the rear support loop engages a bottom loop 23 formed by turning the lower end of a rear strap 24 upwards and securing the free end onto a button 25 attached on the strap 24. The top end of the strap 24 is formed with fixed loop 26 slidably mounted on the rear section 12 and an absorbent pad 27 of cellulose, sponge, or cotton is formed into the shape of a block as clearly shown in Fig. 4 and engages in the recess 20. The sponge material referred to may either be natural sponge or artificial sponge such as rubber sponge.

45 In the modified form illustrated in Figs. 6 and 7 a pad support 17' has been illustrated formed with apertures 28 thru which a band 29 passes. This band consists of a front loop portion 30, a rear loop portion 31 and longitudinal sides 32. Stitches 30' pass thru the pad support 17' and the band 29 near the loop portion 30 for holding the loop portion 30 against being drawn into the pad support 17'. An absorbent pad 27' is formed with longitudinal grooves 33 at its sides for engagement by the longitudinal sides 32 of the band 29.

50 As this pad support is supported by the waist strap tension is applied on the loops 30 and 31 which draw the longitudinal sides 32 taut and hold the absorbent pad 27' in place. For removing the pad it is necessary to loosen the loop 31, i. e., allowing the pad to be drawn up and at the same time allowing the loop 31 to pass inwards into the recess 20 for slackening itself so that the pad

can be drawn up. Once the pad is lifted out of the pad support the sides 32 may be disengaged from the grooves 33.

In operation of the device the absorbent pad may be used in the customary way and when desired removed for washing. These pads, whether made from cotton, cellulose, or sponge must contain sufficient firmness for maintaining their block formation so that they may snugly engage in the recesses 20 shaped for receiving them.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In a catamenial bandage, a pad support having a bottom and sides forming a recess, an absorbent block shaped pad for engaging in the recess, and a band passed thru apertures in the pad support and consisting of front and rear loop portions and longitudinal sides, the said pad being formed with longitudinal grooves engaged by the longitudinal sides for holding the pad against displacement.

2. In a catamenial bandage, a pad support having a bottom and sides forming a recess, an absorbent block shaped pad for engaging in the recess, a band passed thru apertures in the pad support and consisting of front and rear loop portions and longitudinal sides, stitches passing thru the band and pad support near one of the loops, and the said pad being formed with longitudinal grooves engaged by the longitudinal sides for holding the pad against displacement.

In testimony whereof I have affixed my signature.

JOSEPH REICH.
